TERMIT SHIELD

James D. Tennison, 450 N. Bellevue, Memphis, Tenn.
Original application Nov. 30, 1950, Ser. No. 198,359, now
Patent No. 2,674,765, dated Apr. 13, 1954. Divided
and this application Apr. 12, 1954, Ser. No. 422,555
2 Claims. (Cl. 50—73)

This invention relates to termite shields and more particularly to a lock joint whereby a plurality of such shields may be readily and conveniently assembled without requiring the use of special or other tools, equipment, or other materials.

The instant application is a division of co-pending application Serial No. 198,359, filed November 30, 1950, and now Patent No. 2,674,765.

Termite shields of the character with which we are here concerned are presently employed with increasing success in the protection of wooden portions of buildings or other structures against the destructive action of termites and other wood boring insects. The necessity for such protection is particularly great in structures having no basement, or subterranean portion, where wooden foundations are in contact with or substantially close to the ground.

Concrete or similar footings are generally employed, in structures of this character, and for effective protection against termites and other insects, metallic shields are positioned either within or above these footings with the wooden rafters, joists, and the like, supported thereabove. For convenience of installation as well as economy of manufacture these metallic termite shields have generally been provided in convenient, fixed lengths and, since the structure walls are of much greater extent than the conventional lengths of such shields, a plurality of shields are appropriately assembled and installed in accordance with the size of the structure and the length of the walls thereof. For effective results, such assembly requires a particularly secure joint between adjacent shields and various methods have been employed to attain this end.

Present day practices call for a soldered joint, which is particularly expensive, or for the use of resilient and frictional connecting members, the latter method adding materially to the expense of installation, requiring the manufacture of relatively costly connecting elements and skilled labor for the assembly thereof at the site of the construction.

The majority of such connectors as are manufactured in accordance with prior art teachings have proven unsatisfactory in actual practice, either by reason of an ineffective joint or through deterioration at the joint through the action of the elements.

A generally satisfactory termite shield comprises a metallic sheet having corrosion resistant properties and which projects in a substantially horizontal direction a minimum of two inches beyond each side of a vertically disposed foundation wall or footing, the longitudinal edges of the shield being bent downwardly at an angle on the order of 45° from the horizontal, the width of such bent or angularly inclined portions also being approximately two inches. Thus, since each shield extends transversely in a horizontal direction and inclines downwardly at opposite sides or edges thereof, the provision of an effective locking joint at the points where angular inclination commences is inherently difficult. Moreover, since in the majority of instances the weight of the structure is supported at least in part upon the horizontally disposed portions of the joints, a degree of distortion takes place, where separate resilient or frictional connecting elements are employed, which is adverse to the effectiveness of the seal adjacent the outer or inclined portions of each joint. Accordingly, it is a major object of the present invention

2

to provide a novel joint for termite shields whereby a plurality of individual shields may be rapidly and conveniently assembled with no requirement for the use of tools, other materials, or particularly skilled labor.

It is a further object of the present invention to provide a novel termite shield manufactured with a joint as an integral portion of the extremity thereof so that opposed extremities of adjacent shields may be interengaged, providing an efficient and secure lock therebetween.

It is a further object of the present invention to provide a novel lock joint for termite shields which will extend transversely across said shields for the entire width thereof, including horizontally disposed central portion and downwardly inclined edges.

It is a still further object of the invention to provide an efficient and resilient lock joint for the extremities of termite shields whereby frictional engagement is had across the entire width of the shield and for a substantial area thereof, such frictional engagement being inherent to the method of fabrication of the locking extremities of the shields.

It is a still further object of the present invention to provide an efficient and resilient lock joint for the extremities of termite shields which will be equally applicable for use upon shields of varying surface conformation including, among others, shields having straight longitudinal axes, shields having arcuate longitudinal axes, right-angle shields intended for use at the corners of structures, and T-shaped shields intended for use at the juncture of side and transverse footings.

Other objects and the nature and advantages of the invention will be apparent from the following description taken in conjunction with the accompanying drawing, wherein:

FIG. 1 is a fragmentary perspective view, illustrating in expanded relationship the opposed extremities of adjacent termite shield sections where one extremity of each shield section is provided with the novel lock joint of the instant invention;

FIG. 2, an enlarged detail sectional view illustrating the extremities of the shield sections disclosed in FIG. 1 in engaged position;

FIG. 3, an enlarged detail sectional view somewhat similar to FIG. 2, illustrating a further modified form of termite shield and joint; and

FIG. 4, a perspective view on a somewhat reduced scale of a termite shield section having a lock joint at but one extremity and provided with a single downwardly inclined edge portion.

As illustrated in FIGS. 1 and 2 of the drawing, the termite shield section includes a horizontally disposed central portion 10 and inclined edge portions 11 which extend downwardly from the horizontal, at an angle on the order of 45°. Desirably, the width of the central portion 10 of the shield is sufficient to extend a minimum of two inches beyond the vertical walls of the footing of other structural element upon which the shield is intended to be mounted. The width of each of the downwardly inclined portions 11 is also preferably two inches, dimensions of this character having proven entirely adequate and being in excess of that which may be traversed by a termite in direct flight. The length of each termite section is such as to permit of convenient handling, without undue weight, and may be either standardized or in accordance with the particular structure. If desired, but a single inclined surface 11 may be provided, located on but one side of the shield section, as will be discussed more fully hereinafter. However, for purposes of illustration, two such surfaces have been disclosed in FIG. 1.

The extremity 12 of the shield section is of downwardly directed generally S-shaped conformation, the shield section being bent backwardly upon itself to provide a trans-

verse arcuate end portion 13 and an upwardly directed intermediate leg portion 14, the portion thus defined being intended for frictional engagement with the opposed extremity of the adjacent shield section.

The upper extremity of the leg 14 frictionally engages the under surface of the shield section and the shield section is then bent reversely upon itself to provide a transverse arcuate end portion 15 and the horizontally disposed terminal leg 16 of the S-joint. Preferably the leg 16 is disposed in substantial parallelism with respect to the shield proper and extends beyond the arcuate end 13, the upper surface of this leg frictionally engaging the lower surface of the intermediate leg 14 at the point of juncture with the transverse arcuate extremity 13. By the arrangement thus described, spaces 17 and 18 are provided above and below the intermediate leg 14, respectively, for a purpose to be discussed more fully hereinafter.

One end of each shield section is provided with the S-shaped extremity described in detail hereabove, the opposed extremity 45 remaining in the respective planes of the central portion 10 and inclined edge portions 11.

With the form of shield section thus described, assembly of adjacent sections is a particularly simple matter. The extremity 45 of one section becomes a male element receivable frictionally within a female element formed by the upwardly directed intermediate leg 14, the arcuate end portion 15, and the horizontally disposed terminal leg 16 of the S-joint of the adjacent shield section, as indicated at 18. Since, in manufacture, the upper surface of the terminal leg 16 frictionally engages the lower surface of the intermediate leg 14 at the point of juncture with the arcuate extremity 13, secure frictional engagement of the shield extremity 45 along the entire length of the terminal leg 16 is assured and a highly effective frictional joint is thus obtained. It will be readily understood that the joint thus described is susceptible of ready assembly and secure frictional engagement between adjacent extremities of shield sections is insured. Moreover, with this form of joint, a heavier gauge of metal may be employed, if desired, than has been practicable heretofore, since the insertion of the male extremity 45 into the S-joint 12 requires no such expansion of the female element as to result in any substantial distortion.

In the modified form of termite shield section illustrated in FIG. 3 of the drawings, the S-joint has been disclosed as offset upwardly from the plane of the shield proper so that the underside of the shield, intended to rest upon a footing or the like, will be substantially flush. This modified form of shield section includes a horizontally disposed central portion 50 and downwardly inclined edge portions 51, one extremity 52 the shield section being of generally S-shaped conformation. Each shield section 50 is provided with an upwardly offset and outwardly angularly inclined portion 53 extending transversely of the shield section adjacent one extremity thereof. The upper extremity of the offset portion 53 merges into the upper leg 54 of the S-joint, the leg 54 being horizontally disposed and in substantial parallelism with respect to the respective planes of the central portion 50 and inclined edge portions 51. At the outer extremity of the leg 54 the shield section is bent backwardly upon itself to provide an arcuate end 55 and an upwardly directed intermediate leg 56, similar to the arcuate extremity 13 and intermediate leg 14, respectively, previously described.

Preferably the upper extremity of the leg 56 frictionally engages the under surface of the shield section which is then bent reversely upon itself to provide an arcuate end 57 and the horizontally disposed terminal leg 58 of the S-joint. Desirably the leg 58 is disposed in substantially the same plane as the central portion 50 and is thus in parallelism with both the shield section and the primary leg 54 of the joint. By the arrangement thus described, spaces 59 and 60, respectively, are provided above and below the intermediate leg 56, the space 60 becoming a female element intended for the secure frictional recep-

tion of the opposed extremity 61 of the adjacent shield section.

The arrangement thus described provides for a substantially flush bottom surface insofar as connected shield sections are concerned, a particularly desirable feature under certain structural conditions or circumstances.

It will be obvious that, if desired, an S-joint 52 may be provided at each edge of the shield section and, where such joints are mirror images of each other, the lock or frictional joints described in connection with the aforementioned co-pending application may be employed, and such arrangements are well within the scope of the present invention. However, for simplicity of installation it has been found desirable to have a joint on but one extremity of each shield section, employing the method of frictional assembly illustrated in FIGURES 2 and 3 of the drawing.

It is also within the scope of the invention to provide termite shield sections provided with an inclined edge portion on but one longitudinal edge thereof. Such a section has been illustrated in FIG. 4 where the shield section includes a horizontally disposed portion 62 and a single downwardly inclined edge portion 63. One extremity of the shield terminates in a downwardly directed substantially S-shaped joint 64, similar to the joint 12 described hereabove, and the opposite extremity 65 of the shield section is intended for frictional engagement within the S-joint of the adjacent shield section. Shield sections of this character are installed in the conventional manner with the inclined edge generally located on the side of a footing or the like removed from any wall structure. Thus the horizontally disposed edge of the sections may be received within wall structure or, where necessary, angularly deformed to comply with specific structural necessity. Obviously, the forms of the invention illustrated in FIGURES 1 through 4 of the drawings may be fabricated with but a single inclined edge without in any manner departing from the inventive concept.

It will be readily apparent that termite shield sections, whether of standardized construction or specially fabricated in accordance with specific or unusual structural requirements, may be manufactured en masse in accordance with the present inventive concept and may be readily and conveniently assembled at the site of the structure, requiring neither special tools, additional materials, or unusually skilled labor. The structure is such that permanently effective joints are provided, insuring against deterioration at the joint per se, heretofore the weakest point of shields of the character with which we are here concerned.

It will be obvious to those skilled in the art that various changes may be made in this device without departing from the spirit of the invention and therefore the invention is not limited by that which is shown in the drawing and described in the specification but only as indicated in the appended claims.

What is claimed is:

1. A termite shield section having a central horizontally disposed portion and at least one inclined side portion said central horizontally disposed portion extending continuously in a single plane to one extremity of the shield section and providing a male element, the opposite extremity of said section being of generally S-shaped conformation, said extremity being bent downwardly and reversely upon itself to provide a first transverse arcuate end portion and an upwardly inclined intermediate leg portion, the upper extremity of said intermediate leg portion frictionally engaging the under surface of said shield section, said intermediate leg portion being bent downwardly and reversely upon itself to provide a second transverse arcuate end portion and a terminal leg of sufficient length to extend beyond said first transverse arcuate end portion, the upper surface of said terminal leg frictionally engaging the lower surface of said first

arcuate end portion, said upwardly inclined intermediate leg portion and terminal leg together with the arcuate end portion therebetween comprising a female element for the frictional reception and secure retention of the opposed extremity of an adjacent shield section, said S-shaped extremity being upwardly offset from the plane of the horizontally disposed central portion of said shield so that said horizontally disposed portion and said terminal leg portion lie in the same horizontal plane.

2. A joint for a termite shield formed from a plurality of shield sections, each section having a central horizontally disposed portion and at least one downwardly inclined side portion said central horizontally disposed portion extending continuously in a single plane to one extremity of the shield section and providing a male element, the opposite extremity of each section being upwardly offset and of generally S-shaped conformation, said extremity being bent downwardly and reversely upon itself to provide a first arcuate end portion and an upwardly inclined intermediate leg portion, the upper extremity of said intermediate leg portion frictionally engaging the under surface of said shield section, said intermediate leg portion being bent downwardly and reversely upon itself to provide a second transverse arcuate end portion and a terminal leg of sufficient length to extend 25

10
